(57) **CLAIM**

The ornamental design for a mining lamp, as shown and described.

DESCRIPTION

FIG. 1 is a perspective view of a mining lamp showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along line 9-9 in FIG. 6.

The dashed broken lines illustrate portions of the mining lamp and form no part of the claimed design.
